US00D840968S

(12) **United States Design Patent** (10) **Patent No.:** **US D840,968 S**
(45) **Date of Patent:** **** Feb. 19, 2019**

(54) **WIRELESS HEADSET**

(71) Applicant: **SPIGEN KOREA CO., LTD.**, Seoul (KR)

(72) Inventors: **Sang Yoon Shin**, Seoul (KR); **Chung Hae Kwon**, Seoul (KR)

(73) Assignee: **SPIGEN KOREA CO., LTD.**, Seoul (KR)

(**) Term: **15 Years**

(21) Appl. No.: **29/609,119**

(22) Filed: **Jun. 28, 2017**

Related U.S. Application Data

(63) Continuation of application No. 29/605,073, filed on May 23, 2017, now Pat. No. Des. 830,335.

(51) **LOC (11) Cl.** **14-01**

(52) **U.S. Cl.**

USPC **D14/205**

(57) **CLAIM**

The ornamental design for wireless headset, as shown and described.

DESCRIPTION

FIG. 1 is a front perspective view of a wireless headset showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is right side elevational view thereof;

FIG. 7 is a top plan view thereof;

FIG. 8 is a bottom plan view thereof; and,

FIG. 9 is a front perspective view thereof illustrating an earbud being extended.

The broken line showing of environment is for illustrative purposes only and forms no part of the claimed design.

1 Claim, 9 Drawing Sheets
